UNITED STATES PATENT OFFICE

152,199

DESIGN FOR A COMBINED DIAL AND HANDS FOR A CLOCK

Willard C. Jenkins, Wilmington, Del.

Application March 20, 1947, Serial No. 137,783

Term of patent 7 years

(Cl. D42—10)

To all whom it may concern:

Be it known that I, Willard C. Jenkins, a citizen of the United States, residing at Wilmington, in the county of New Castle and State of Delaware, have invented a new, original, and ornamental Design for a Combined Dial and Hands for a Clock, of which the following is a specification, reference being had to the accompanying drawings, forming part thereof.

In the drawings:

Fig. 1 is a face view, and

Fig. 2 is a side view of a combined dial and hands for a clock, showing my new design.

The essential features of my design reside in the parts shown in full lines.

I claim:

The ornamental design for a combined dial and

hands for a clock, substantially as shown and described.

WILLARD C. JENKINS.
